DESIGN FOR A VEHICLE WHEEL

Carolus L. Eksergian and Warren H. Farr, Detroit, Mich., assignors to Budd Wheel Company, Philadelphia, Pa., a corporation of Pennsylvania

Application March 29, 1938, Serial No. 76,151

Term of patent 14 years

To all whom it may concern:

Be it known that we, Carolus L. Eksergian and Warren H. Farr, citizens of the United States, residing at Detroit, in the county of Wayne and State of Michigan, have invented a new, original, and ornamental Design for a Vehicle Wheel, of which the following is a specification, reference being had to the accompanying drawing, which forms a part thereof.

Figure 1 is a perspective view of a vehicle wheel embodying our new design.

Figure 2 is an enlarged fragmentary side elevation of the wheel.

Figure 3 is an enlarged diagrammatic outline of an axial cross section of the wheel taken on the line 3—3 of Figure 2.

Figure 4 is a diagrammatic outline of a section taken on the line 4—4 of Figure 2.

A dominant feature of the design consists in the provision of an annular series of narrow elongated openings arranged closely adjacent to the rim, the openings being formed at the bottoms of shallow depressions in the convex outer face of the wheel, said depressions terminating a substantial distance radially outwardly of the hub cap.

We claim:

The ornamental design for a vehicle wheel, substantially as shown and described.

CAROLUS L. EKSERGIAN.
WARREN H. FARR.
